H. I. RAYMOND, JR

ELEVATING TRUCK PLATFORM

Filed Dec. 18, 1920

FIG. 1.

FIG. 2.

FIG. 3.

INVENTOR.
HENRY I. RAYMOND, JR.

BY *Henry Raymond*

ATTORNEY.

UNITED STATES PATENT OFFICE.

HENRY I. RAYMOND, JR., OF INDIANAPOLIS, INDIANA, ASSIGNOR TO THE ENTERPRISE IRON WORKS, OF INDIANAPOLIS, INDIANA, A CORPORATION OF INDIANA.

ELEVATING-TRUCK PLATFORM.

Application filed December 18, 1920. Serial No. 431,699.

To all whom it may concern:

Be it known that I, HENRY I. RAYMOND, Jr., a citizen of the United States, residing at Indianapolis, in the county of Marion and State of Indiana, have invented certain new and useful Improvements in Elevating-Truck Platforms, of which the following is a specification.

This invention relates to platforms, and particularly to that class adapted to be used in connection with elevating or lifting trucks, either of the hand variety or electrically operated, the prime feature of the invention being the provision of a strong and durable platform, and one requiring a minimum amount of material for construction, while at the same time providing an extremely strong and durable structure.

A further feature of the invention is in so constructing the parts of the platform that it may be shipped in knock-down formation and readily assembled for use, thereby minimizing the expense in drayage and freightage.

Other objects and advantages will be hereinafter more fully set forth and pointed out in the accompanying specification.

In the accompanying drawings which are made a part of this application,

Figure 1 is a top plan view of a platform ready for use,

Figure 2 is a side elevation thereof with one of the boards shown in section, and

Figure 3 is an end elevation of the platform.

Referring to the drawings, 1 indicates the frame or rails of the platform which are preferably constructed of angle iron and cut in proper lengths, said rails being ar-

ranged in pairs and adapted to support the ends of floor boards 2, bolts 3 being em- ployed for fastening the floor boards to the frame. The boards 2 are provided, adjacent their ends, with countersunk openings

4 into which the heads 5 of the bolts are seated, a washer 6 being entered in the countersunk openings and surrounding the bolts below the heads while a lock washer 6a surrounds the bolts below the flanges of the rails, so that when the nuts 7 are turned onto the bolts they will be securely locked in position.

This platform is designed primarily for use in connection with elevating or lifting trucks, and in order to support the floor surface of the platform a sufficient distance above the usual floor in order to admit the passage of the truck below the floor boards, supports are provided which are preferably constructed of metal and likewise preferably formed of angle iron, the vertical portions of the supports preferably flaring outwardly from each other to give bracing action thereto, while the lower connecting portions of the supports are extended a distance horizontally, thereby providing feet 12 with wide flat bearing surfaces. The upper ends of the legs 8 abut against the under surface of the horizontal flange of the rails 1, while one flange of the legs rests against the depending flange of the rails and the legs are secured to the rails in any suitable manner, as by means of rivets 9, or the like, which pass through the abutting flanges of the rails. The pairs of supports along opposite edges of the platform may be further reinforced through the medium of brace bars 10, the ends of which are secured to the inner vertical portions of the legs 8 by means of rivets 11, or the like.

It will be understood, of course, that instead of using the rivets 9 and 11, as shown, bolts may be substituted therefor, or these parts may be secured together in any suitable manner.

By constructing the platform in the manner shown and described the parts thereof may be shipped in knock-down condition and readily assembled after they reach their destination, thereby greatly conserving on the cost of shipping and transporting expense, and in view of the manner in which the various parts are connected together and braced they will be very substantial, and will support heavy weights without becoming wracked or broken from ordinary use.

Having thus fully described my said invention, what I claim as new and desire to secure by Letters Patent, is:

In a truck platform, a pair of longitudinal frame members of angle iron each having a vertical flange and a horizontal flange, transverse load-supporting members secured to said frame members and U-shaped sup-

2
ports having continuous flanges at right angles to each other forming flat foot portions and oppositely extending leg portions attached to the vertical flanges of a frame member, substantially as set forth.

In witness whereof, I have hereunto set my hand and seal at Indianapolis, Indiana,

this 14th day of December, A. D. nineteen hundred and twenty.

HENRY I. RAYMOND, JR. [L.S.]
Witnesses:

CAREY S. FRYE,
M. L. SHULER.
